UNITED STATES PATENT OFFICE.

FRANK YOKEL, OF AVALON, PENNSYLVANIA, ASSIGNOR TO PITTSBURGH LAMP, BRASS & GLASS COMPANY, OF PITTSBURGH, PENNSYLVANIA, A CORPORATION OF NEW JERSEY.

DESIGN FOR A LAMP STANDARD.

Application filed April 5, 1923. Serial No. 5,704. Term of patent 7 years.

To all whom it may concern:

Be it known that I, FRANK YOKEL, a citizen of the United States, residing at Avalon, in the county of Allegheny and State of Pennsylvania, have invented a new, original, and ornamental Design for a Lamp Standard, of which the following is a specification, reference being had to the accompanying drawings, forming part thereof.

In the drawings:

Fig. 1 is a side elevational view showing my new design; and

Fig. 2 is a top plan view thereof, showing the bottom partly broken away.

I claim:

The ornamental design for a lamp standard, as shown.

FRANK YOKEL.
